UNITED STATES PATENT OFFICE.

OLIVE HILLS, OF WINDSOR, ENGLAND.

HATBAND.

Application filed August 12, 1924, Serial No. 731,625, and in Great Britain September 24, 1923.

This invention relates to hat bands, as fitted to ladies' and men's soft hats exteriorly around the base of the crown and provides a made-up bow-band which can be fitted 5 in position and will fit the hat crown snugly without the necessity of shaping or stitching the band.

The invention relates to detachable bow-bands of the kind wherein the band proper 10 is discontinued for a distance, such discontinued part being occupied by a single elastic insertion substantially of equal width to the band itself, which completes and closes the band, the said elastic insertion being hidden 15 under the bow, said bow consisting of a separate piece sewn by one of its ends to the band proper, its loop being loosely mounted on the elastic insertion, or being formed by doubling back the ends of the 20 bow.

In previous proposals of the foregoing kind the elastic insertion has been of rectangular shape, its ends being parallel with one another, but since the crown of the hat 25 usually tapers towards the top the result has been that the band stands away at its top edge, from the crown.

The present invention, which has for its 30 object to obviate this disadvantage embodies an elastic insertion consisting of a single elastic strip substantially the full width of the band as has been previously proposed, but the present invention is characterized in that the said insertion has the shape of a 35 symmetrical trapezoid or is otherwise shaped so that its sides taper towards its top edge. The result is that the band is caused to assume a shape which conforms more or less to the tapering contour of the hat crown, 40 so that when fitted in place its top edge does not stand away from said crown.

A further feature consists in the formation 45 of the bow as will be hereinafter described.

The invention will be the more readily 50 understood by reference to the accompanying sheet of drawings illustrating two preferred constructions of band in accordance therewith, and wherein:—

Figure 1 is a perspective view of one 55 construction of band, the bow being disarranged in order to clearly show the construction of the band.

Figure 2 is a similar view showing the 55 bow in place, the band being ready for application to a hat, and

Figure 3 is an enlarged edge view of a portion of the band in the vicinity of the bow.

Figure 4 is a perspective view of a modification, the bow being disarranged.

Referring to Figures 1, 2 and 3, the band shown therein consists of a main strip 1 which nearly forms a complete loop but is discontinued for a short distance; that is to say there is a gap between its two ends. Such gap is occupied by an elastic insertion 2. The said elastic insertion 2 has the shape of a symmetrical trapezoid as shown or is otherwise shaped so that its side edges 70 taper together towards its top edge, the end edges of the band 1, to which said side edges of the elastic member 2, are stitched being cut obliquely to correspond. The result is that the band assumes a slight cone shape 75 which conforms more or less to the tapering contour of the hat crown, so that when fitted in place its top edge does not stand away from the hat crown. The bow consists of a separate doubled strip 3 of similar material to the band itself stitched at its point of doubling 4 to the band near to the left hand side edge of the elastic insertion 2, and a loop or sleeve 5 of the same material 80 which encircles the band and also the double thickness of the strip 3, when arranged in position as shown in Figures 2 and 3. Said sleeve 5 may be loosely mounted or may be stitched or otherwise secured to the strip 3 or to the band 1 or elastic insertion 2. 85

A modification of the foregoing construction is shown in Figure 4, wherein the bow is formed by continuing the strip 1 at one end past the point 6 where the elastic insertion is stitched to it. The continued part is doubled back from such point 6 for a short distance and then back again forming the rear thickness 7 of the bow. At the end of such part 7, the continued part is again doubled back to form the front thickness 8. 95

In a further modification, the continued part of the strip 1, from the point 6 may, instead of being doubled back from such point, pass directly across the elastic insertion 2 exteriorly and be doubled back 105 when beyond such insertion.

I claim:—

A hat band comprising a strip of relatively inelastic material adapted to encircle a hat crown and having parallel longitudinal edges, one of which is longer than the other, an insert of elastic material substan- 110

tially trapezoidal in shape with the longer edge thereof alined with the shorter edges of the strip and at the bottom of the said strip, the end portions of the strip and the insert 5 being joined with each other by seams disposed along oblique lines, said seams diverging from the longer edge of the strip to-

wards the shorter edge, a bow attached to said strip, and a loop slidable on said strip towards and away from said bow. 10

In testimony whereof I have hereunto affixed my signature this 23rd day of July, 1924.

OLIVE HILLS.
